The ornamental design for the disposable diaper dispenser, as shown and described.

DESCRIPTION

FIG. 1 is a front elevational view of the disposable diaper dispenser showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a cross-sectional view thereof taken along line 7—7 of FIG. 5, the broken line showing of the stack of diapers for illustrative purposes only and forming no part of the claimed design.
